FLANGING PRESS DELIVERY DEVICE

André Brémont, Paris, France, assignor to
Société des Agrafes Françaises (Societe Anonyme), Paris, FranceApplication August 18, 1931, Serial No. 557,881
In France August 27, 1930

9 Claims. (Cl. 113—113)

This invention relates to an automatic device designed for delivering blanks having the shape of a cap, that is of an inverted cup, to a flanging or a cutting press, said device taking the blanks which are loose in a hopper and bringing them to the punch in the required position.

Now as the cupped blank must be fitted upon the punch this operation is actually done by hand but the automatic presses generally used make it very dangerous. The danger could only be avoided by stopping the machine after every operation but in that case the output is not satisfactory and the consequent wear of the gears is very great.

15 It will be seen from the above that the present invention constitutes an important progress in that branch of industry as it allows of automatically effecting a correct adjustment of the cupped blank in synchronism with the operation of the press and that consequently the delivery is uninterrupted and the output is as great as possible.

The present device comprises in combination:

(a) A mechanism for removing and positioning the blanks from the magazine and feeding 25 them in the desired position.

(b) A sliding channel in which said blanks enter and which directs them towards the press.

(c) Another mechanism designed to take the blanks one by one and to fit them upon the 30 punching die.

The first mechanism, that is the one for selecting the blanks in the magazine comprises a plate provided with fingers which rotates in the midst of the blanks contained in the magazine 35 in such a manner that the latter being moved in all directions are caught by the fingers which project inside the hollows of the blanks.

The magazine is provided with an inclined circumferential side which at its lower part allows the blanks which are endangered of being 40 wedged in, to slide upwards and to thus avoid being crushed by the blanks guided by the plate.

The magazine is also provided at its upper part with a pliable blade that removes the blanks 45 which have not been caught by the fingers and thus prevents their reaching the channel opening.

The blank guiding channel is characterized in that it is provided with an opening and with 50 a branch channel to return the blanks in excess to the magazine thus avoiding their being damaged by pressure when the bottom of the channel is closed, during the stamping operation, the gripping and hooking plate still feeding blanks 55 to the channel.

The channel is provided at its opening with a grooved incline which allows the fingers to draw back as the blanks move upwards.

The third mechanism in the present device which is designed to take the cupped blanks one by one as they come out of the channel to fit them upon the punching die and comprises in combination an oscillating arm which is alternately moved downwards and upwards by a system of connecting rods and cams actuated by the driving shaft of the press itself, and selecting means operated by vacuum so that the blanks are caused to adhere by suction to the carrier arm which can freely swing back to take a new blank 60 the preceding one remaining on the punching die.

Another characteristic of the above blank feeding and setting mechanism is that the horizontal movements of the feed arm are produced by means of a cam and of a counter cam so that they take place with great accuracy and that consequently all risk of damage is avoided. On the other hand its ascending movement is the only one of its vertical displacements which is produced by a cam its descent being actuated 75 by a spring so that it is substantially impossible for the blank to be inaccurately set in position, and the press is not in danger of being damaged.

Still another characteristic of the present invention is that the oscillating blank feed arm which brings the blanks upon the punch pushes back the channel closing means, so that a new blank may be sucked by the pneumatic device 80 and thus adhere to said arm.

90 The annexed drawings show by way of example a mode of execution of my invention.

Figs. 1, 1^b, 1^a joining on lines Y Y and X X form a side elevation of the whole apparatus the magazine being supposed brought on a front 95 plane.

Fig. 2 is a front view of the blank feed arm driving means.

Fig. 3 is a part plan view of the mechanism shown in Fig. 2.

Figs. 4 and 4^a joining on the line z—z, form 100 a front view of the delivery magazine.

Fig. 5 is a detail view showing the selecting plate and the channel.

As will be seen in the drawings the apparatus 105 comprises a cylindro-conical magazine hopper 1 secured by means of an arm 2 upon an inclined support 3 secured itself upon a cross-beam 4 preferably directed in such a manner that its extremity is visible to the workwoman placed in 110

front of the press. In the drawings the whole of this mechanism has been brought to the front, the hopper being turned backwards in order to facilitate the understanding.

5 A rotary plate 5 parallel with the inclined support 3 is arranged inside the hopper. It bears upon the inclined support 3 through the intermediary of a roller bearing abutment 6.

10 The rotary plate 5 is integral with a gear 7 (Figs. 1^a and 4) which is driven by means of a pinion 8 (Fig. 4) carrying upon its shaft a pulley 9 actuated by another pulley 10, by means of a cord 11, said pulley 10 being actuated by the general press driving system.

15 The rotary plate 5 carries a set of fingers 12 arranged circumferentially which are designed to catch the blanks loosely collected at the bottom of the hopper by projecting into the hollow of the cupped blanks and to bring them to a channel guide 13 whose opening is flared and is positioned tangential to the circumference of the axes of the fingers 12.

20 A flexible blade 14 (Fig. 4) is secured upon the hopper wall, it is directed inwards and shaped so as to push back to the bottom of the hopper the blanks which have not been caught but would reach the channel opening as well as those that would eventually cap a blank previously caught.

25 It will be noted that owing to the existence of the conical hopper wall 1^a no wedging effect can take place in the lower part of said hopper between the loose blanks and those already caught on the fingers 12, the former obviously will be caused to slide up the incline of said wall 1^a.

30 The opening of the channel 13 is suitably flared at 13^b and its bottom which is cut out and rises gradually is provided with two spring blades 15 on each side of a groove 16 having sufficient depth to allow the passage and the withdrawal of the fingers under the guide as the blanks move upwards along said guide which is partially covered along its whole length by a cover 13^a.

35 The blanks as they move along in the channel push those in front further on, the impetus being given every time by the newly presented blank which is being pushed in the opening by its finger.

40 It will hereinafter be seen that the outlet end of the channel is periodically closed and consequently as the rotary plate 5 rotates permanently the blanks might be crushed in the channel. In order to prevent this, the latter is provided in its most strongly curved portion with an opening 17 through which the blanks in excess may be slid out and may be returned to the hopper through a chute 18.

45 As already stated, the channel 13 rises a little at the opening, at the starting point of the rotary plate 5, then descends gradually as it follows any desired path and opens in a stationary slide 19 mounted upon a support 20 secured to the press frame B (Fig. 1^b).

50 An obturating sliding device 21 which a spring 22 tends to always maintain in its closed position is placed across the end of the slide 19. It is periodically pushed back by the side of an arm 23 which may rotate with a shaft 24ⁱ perpendicular to the plane of the press table which is usually inclined.

55 The arm 23 is provided at its end with a recess 25 having a half cylindrical shaped wall whose radius is equal to that of the blank and which is provided with an opening 23^a in communication with a rigid tube 26 connected by means of

a hose 26^a (Figs. 1 and 3) to a vacuum source, preferably an exhaustor actuated by the general motion of the machine, so that when the arm is in the position in which the obturating device is disengaged the suction opening which is located at the opening of the curved wall 25 of arm 23 produces an adherence by suction of the blank which presents itself at the end of the slide 19 and holds the blank against said wall 25.

60 At the top of arm 23 is mounted a plate 27 operating as a pressure plate for the cupped blank and which serves to press the blank on the punching die when the arm 23, containing the blank, is lowered over the said die.

65 The arm carrying shaft 24ⁱ is provided with grooves 60 at its lower end (Fig. 2) where it carries a crank pin 28 which is provided with corresponding projections and is designed to rotate said shaft. The shaft 24ⁱ is guided in a frame 29. The crank pin 28 is connected with ball and socket joint at 30 (Fig. 3) to a connecting rod 31 itself connected at its other end at 32 by means of a ball and socket joint with the arm 33^a, of a two-arm lever 33^a—33^b. The ball and socket joint between 31 and 33^a is adjustably positioned in a slot 34 in arm 33^a. The two-arm lever is pivotally connected at a fixed point 35, the other arm 33^b being pivotally connected at 36 with a connecting rod which moves in a vertical plane perpendicular to the crankshaft 38 of the machine. The head 37^a of the connecting rod 37, which is bored at 37^b carries two rollers 39, 40, one on either side.

70 The roller 39 engages a cam 41 and the roller 40 engages a counter-cam 42 both cams being secured upon the machine shaft 38, in such a manner that the cam 41 rotates the arm 23 which carries the blank (Fig. 3) by the intermediary of the connecting rod 31 and of the crank pin 28, moving it from the slide 19 to the punch 43, the counter cam 42 causing the backward rotation which returns said arm in a position opposite the guide.

75 The shaft 24ⁱ is connected by means of a sleeve 44 by the intermediary of ball abutments 45, 46 to a shaft 24^s of similar construction so that the rotation of shaft 24ⁱ does not cause rotation of shaft 24^s but said shaft 24ⁱ may be drawn along in the longitudinal displacements of shaft 24^s. The latter carries at the top a head 47 which is provided with an eye 47^a for the passage of the main drive shaft 38 of the press and carries an upper roller 48 engaging a cam 49 fixed upon shaft 38 and consequently capable of causing the upward movement of the double shaft 24^s—24ⁱ. The return descending movements of the system are effected by a spring 50 interposed between the sleeve 44 and a stationary abutment 51, fixedly mounted on said shaft 24^s. The arm 23 is keyed to shaft 24ⁱ so as to be rotatable as well as vertically displaceable therewith. Shaft 24ⁱ is rotated in turn by means of crank pin 28. In order to prevent a vertical displacement of the crank pin 28, it is provided with projections corresponding to the grooves 60 of the shaft 24ⁱ, whereby the shaft is permitted to slide vertically with respect to the crank pin 28 but the crank pin may nevertheless rotate the shaft 24ⁱ.

80 The shape of the counter-cam 42 and of the cam 49 is devised so that the return upward movement of the arm by the cam 49 and its horizontal return rotation by means of the cam 42 take place substantially at the same time but with a slight advance of the horizontal rotary movement, to break the connection between the 15^a

suction tube 26 and the cupped blank which has been fitted onto the punching die so that the blank fitted on the punch is not removed with the arm 23 upon its return movement.

5 The operation is as follows:

The fingers 12 of the plate 5 as they pass through the heap of blanks project into the hollow of some of them and take them along towards the channel 13. As they come upon the 10 spring blade 16 at the channel inlet, they move up the incline so that the fingers draw back in and under the slot of said spring blade and of the bottom.

The blanks pile up in the channel and those in 15 excess come out through opening 17 and return to the hopper.

The foremost blank, that is the one at the end of the slide 19 is stopped by the obturating sliding device 21.

20 When the oscillating arm 23 comes opposite the guide and pushes back the obturating sliding device 21, a blank is drawn by suction and "sticks" to said arm. At that instant the cam 41 rotates the crank pin 28 consequently also the arm 23 from left to right, which latter brings the blank above the punch. As the cam 49 now allows the 25 downward movement of the roller 48, the spring 50 returns both shafts 24^a—24^b downwards and thereby lowers the arm 23 which owing to the support given by its cover 27 places the blank on the punch head.

The action of the cam 42 then moves the connecting rod system in the opposite direction and the crank pin 28 is rotated backwards drawing 30 the arm 23 towards the channel. Simultaneously to this displacement and with a slight delay at the origin, so that the blank remains in engagement with the punch without risking of being drawn away by the suction effect, the double shaft 40 24^a—24^b is moved upwards by the cam 49, so that the arm 23 effects an angular and an ascending movement simultaneously, these movements bringing said arm opposite the slide 19 and on its level. The latter which had been closed by the 45 obturating sliding device 21 is now again open and the cycle begins again.

The punching takes place in the interval as soon as the arm 23 is no longer perpendicular to the punch.

50 It will be understood that the construction of the apparatus which has been described and illustrated is by no means limitative and that the various movements may be produced by any known equivalent mechanical devices.

55 It will also be understood that the invention comprises various applications and that according to the blank and to the stage of punching there may be obtained by changing the guides and the carrier arm a set of devices which will feed a series of machines.

Lastly, the invention may be applied to presses of all kinds and to machine tools in which the blank is brought to the capped position.

What I claim and desire to secure by Letters Patent of the United States is:

1. In a flanging press for delivering and setting cap-shaped blanks, the combination which comprises, a magazine hopper to contain the blanks, a rotary plate arranged in the bottom of said hopper and provided with fingers to catch some of the blanks from the mass of blanks piled up in the hopper, a channel guide to direct said blanks to the press, a blank carrier arm suitably shaped at its end to engage the blanks and provided with an opening connected to a vacuum source for

connecting said blank to said arm, a punch spaced from said channel guide and a mechanism for actuating said arm in synchronism with the operation of the press to take the blanks at the end of the guide, carry them over the punch and cap the latter.

2. In a flanging press for delivering and setting cup-shaped blanks the combination which comprises, a crankshaft for driving said press, a magazine hopper to contain the blanks, a rotary plate arranged in the bottom of said hopper and provided with fingers to catch some of the blanks from the mass of blanks piled up in the hopper, a guide to direct the blanks to the press, a punch spaced from said guide, a movable blank carrier arm to engage the blanks, and a mechanism driven by the press crankshaft so as to cause said arm to accomplish a rotary movement from the guide to the punch, then a downward movement to cap the punch, a re-ascending movement to return to the level of the guide end and then return to its original position.

3. In a flanging press for delivering and setting cap-shaped blanks the combination which comprises, a crankshaft for driving said press, a magazine hopper to contain the blanks, a rotary plate arranged in the bottom of said hopper and provided with fingers to catch some of the blanks from the mass of blanks piled up in the hopper, a guide to direct said blanks to the press, a punch spaced from said guide, a movable blank carrier arm designed to engage the blanks, a rotary shaft driven by the crankshaft of the press to actuate said arm, a second shaft longitudinally but not rotatively connected with said rotary shaft actuated by the vertical displacements, and a mechanism actuating the rotary shaft and the second shaft in order to impart to the blank carrier arm the descending re-ascending and return alternate rotary movements required to bring the blanks over the punch, cap it and return to its first position.

4. In a flanging press for delivering and setting cap-shaped blanks, the combination which comprises, a magazine-hopper to contain the blanks, a rotary plate arranged in the bottom of said hopper and provided with fingers to catch some of the blanks from the mass of blanks piled up in the hopper, a guide to direct the blanks to the press, a punch spaced from said guide, a movable blank carrier arm designed to engage the blanks, a rotary shaft actuating said arm by means of cams from the press crankshaft in order to impart to the blank carrier arm the descending, re-ascending and return alternate rotary movements required to bring the blanks over the punch, cap the latter and return to its first position and means to produce simultaneously the re-ascending and the return movement of the blank carrier arm with a slight retardation of the ascending movement relative to the horizontal return movement.

5. In a flanging press for delivering and setting cap-shaped blanks, the combination which comprises, a crankshaft for driving said press, a magazine-hopper to contain the blanks, a rotary plate arranged in the bottom of said hopper and provided with fingers to catch some of the blanks from the mass piled up in the hopper, a guide to direct said blanks to the press, a punch spaced from said guide, a movable blank carrier arm designed to engage the blanks, a mechanism driven by the crankshaft of the machine in order to impart the descending, re-ascending and return rotary movements required to bring the blanks over the punch, to

cap same, and to return to its first position, and a spring obturating part placed at the guide delivery opening so as to be forced back by the blank carrier arm at the inoperative return stroke of said arm to permit the latter to take up a new blank.

6. In a device for consecutively placing cap-shaped blanks on the punch of a stamping press or the like, a crankshaft provided on said press, means for successively passing said blanks through a slide, a punch spaced from said slide, a movable blank carrier arm to engage the blanks, and a mechanism driven by the press crankshaft in such a manner that the arm will be rotated from the guide to the punch, then downwardly to cap the punch, a re-ascending movement to return to the level of the slide, and then return to its original position.

7. In a device for consecutively placing cap-shaped blanks on the punch of a stamping press or the like, a crankshaft provided on said press, means for successively passing said blanks through a slide, a punch spaced from the slide, a movable blank carrier arm to engage the blanks, a rotatable shaft driven by the crankshaft of the press to actuate said arm, a second shaft longitudinally but not rotatably connected with said rotatable shaft actuated by vertical displacements, and a mechanism for actuating the rotatable shaft and the second shaft so as to impart to the blank carrier arm descending, re-ascending and return alternate rotary movements to bring the blanks over the punch and cap the same.

35

8. In a device for consecutively placing cap-shaped blanks on the punch of a stamping press or the like, a crankshaft provided on said press, means for successively passing said blanks through a slide, a punch spaced from said slide, a movable blank carrier arm to engage the blanks, a rotary shaft actuating said arm by means of cams from the press crankshaft in order to impart to the blank carrier arm descending, re-ascending and return alternate rotary movements required to bring the blanks over the punch, and cap the latter, and means to simultaneously produce the re-ascending and the return movement of the blank carrier arm with a slight retardation of the ascending movement relative to the horizontal return movement.

9. In a device for consecutively placing cap-shaped blanks on the punch of a stamping press or the like, a crankshaft provided on said press, means for successively passing said blanks through a slide provided with a delivery opening, a punch spaced from said slide, a movable blank carrier arm to engage the blanks, a mechanism driven by the crankshaft of the machine in order to impart descending, re-ascending and return rotary movements required to bring the blanks over the punch to cap the same, and a spring obturating element placed at the slide delivery opening so as to be forced back by the blank carrier arm at the inoperative return stroke of said arm to permit the latter to take up a new blank.
